UNITED STATES PATENT OFFICE.

PHILIP H. KORST, OF RACINE, WISCONSIN.

ELECTRIC METER.

SPECIFICATION forming part of Letters Patent No. 432,053, dated July 15, 1890.

Application filed May 27, 1889. Serial No. 312,234. (No model.)

To all whom it may concern:

Be it known that I, PHILIP H. KORST, a citizen of the United States, residing at Racine, county of Racine, and State of Wisconsin, have invented a certain new and useful Electric Meter, of which the following is a specification.

My invention relates to electric meters, particularly such as are used for measuring electricity furnished to houses, and has for its object to furnish convenient means therefor.

It is illustrated in the accompanying drawing, which contains a perspective view of the device with the wiring shown diagrammatically.

A and A' are wires leading from the main through the cut-out box A², provided with the handle A³.

B is a resistance inserted in the conductor A and designed to divert an exceedingly small portion of the current passing through the conductors A and A' into the device.

B' B' are lamps in use.

C is a conductor leading from the conductor

A² at one end of the resistance B to the mercury-box C'. C² is a similar conductor leading from the other end of the resistance to the mercury box C³. Both of these boxes are secured upon the bed C⁴, which bears the fixed armature C⁵, above which is suspended the electro-magnet C⁶.

D is a shaft supported on the bed C⁴ by the springs D' D², and carrying near its middle the electro-magnet or solenoid C⁶ on opposite sides thereof the collars C⁷ C⁸, made of insulating material, and farther on the insulated disks C⁹ and C¹⁰. On one end of the shaft, and rigid therewith, is a drum D³, about which is wrapped the cord D⁴, suspending the weight D⁵.

On this drum is the ratchet-wheel D⁶, adapted to engage the dog D⁷. This dog is pivoted on the arm D⁸, which rises from the bed and is connected with the spring D⁹, which tends to keep dog D⁷ in contact with

the ratchet D⁶. On a ledge D¹⁰ on the arm D⁸ is secured the electro-magnet or solenoid D¹¹, for which the dog D⁷ serves as an armature. From the insulating-collar C⁸ extends in one direction the connecting-arm E and in the opposite direction the connecting-arm E', while from the collar C⁷ extends in one direc-

tion the arm F and in the opposite direction the connecting-arm F'.

G is a brush supported on an arm from the standard D' and bearing lightly against the disk C⁹, and G' is a similar brush bearing against the disk C¹⁰. These disks C⁹ and C¹⁰ are both insulated from the shaft D.

H is a registering-box supported from the standard D² on the platform H' and operated from the shaft D.

J is a conductor leading from the arm E to the arm F', thence to the electro-magnet or solenoid C⁶, and back to the disk C⁹, where connection is made with the brush G. K is a conductor leading from such brush to the storage-battery K' and thence to the brush G'.

L is a conductor leading from the disk C¹⁰ to the arm F and connecting with the arm E'. It will be evident that great change could be made in these various parts, and many of them could be omitted or substitutions made therefor.

M is a conductor leading from the conductor A to the electro-magnet or solenoid D¹¹, and N is a conductor leading thence to the conductor A'.

The use and operation of my invention are as follows: Supposing the parts to be situated as indicated in the drawing, the current of electricity entering on the conductor A and leaving on the conductor A' energizes the lamps B' B'. This current which energizes the lamp also energizes the electro-magnet or solenoid D¹¹, and hence moves the armature-dog D⁷ away from its ratchet D⁶ in opposition to the spring D⁹. The parts are now free and ready for operation. The low resistance B will divert a correspondingly small amount of current from the conductor A onto the conductor C, whence it will pass into the box C', up the arm E, and, since it is intercepted by the insulation-collar C⁸, will pass along the conductor J to the arm F'. Since the arm F' terminates in the air, this current will continue its course through the electro-magnet or solenoid C⁶, energizing the same, thence to the disk C⁹, brush G, by conductor K, to storage-battery K', and by conductor K to brush G' and to the disk C¹⁰, thence to the arm E', and, since this arm also terminates in the air, it will continue its course along conductor L to

the arm F, thence to the mercury-box C³, and thence by conductor C² to conductor A on the opposite side of the resistance B. So long as the storage-battery K' is in a receptive condition and is being charged, the current will pass over the course indicated and continue the energization of the electro-magnet or solenoid C⁶, and, since this magnet or solenoid so energized exercises an influence over the immovable armature C⁵, the entire system will be locked in the position indicated. When the storage-battery has become charged, the counter electro-motive force therefrom will neutralize the current diverted from the conductor A by the resistance B, and a time will arrive when the energization of the electro-magnet or solenoid C⁶ is not sufficient to fix it in the relation illustrated to its immovable armature C⁵, and, acting under the influence of the weight D⁵, which such solenoid has hitherto resisted, the shaft D, together with its various members, will rotate until the opposite end of the solenoid comes into position over the armature C⁵. In this position it is held by the current from the storage-battery, which passes over the following course: From battery K' through conductor K to brush G, disk C⁹, conductor J through the electro-magnet or solenoid C⁶ back to the arm F', thence to the mercury-box C³, along conductor C² to conductor A, during which time the diverted current passes from conductor A along conductor C, mercury-box C', arm E', thence to disk C¹⁰, brush G', and conductor K to battery. When the battery-current and diverted current cease to energize the electro-magnet, the parts will again rotate one-half of a revolution and the first operation be repeated. It will be remembered that in the description of the second operation, the parts having rotated the arms F' and E' are in the mercury-box, and the arms E and F terminate in the air contrary to the positions first above described, and which are indicated in the drawing. When the current is cut out of the house—as, for instance, by operating the handle A³ in cut-out box A²—the current is instantly withdrawn from the magnet or solenoid D¹¹, and the spring D⁹, acting upon the armature-dog D⁷, causes it to engage the ratchet D⁶ and lock the parts in the position in which they then are. The register H is of any desired kind, and is so adjusted with reference to the other parts of the device as that it will indicate the number of revolutions so made by the shaft D, and hence the number of ampère hours furnished to the consumer. When the weight has completed its excursion, the device may be reset by winding up the drum or pulley D³ until the weight is brought to its maximum height. The various connecting devices would preferably be insulated conductors and pass within the various parts of the machine. By the use of the resistance B an exceedingly small portion of the current employed is diverted to operate the meter, and the parts are so arranged that the meas-

urement of the small diverted current, bearing, as it does, a constant relation to the current consumed, will measure or meter the principal current so consumed. It will readily be seen that the current to operate the meter may be diverted in other ways; also, that the application of the charging and discharging of the storage-battery to measuring such current can be utilized in other ways. As indicated on the drawing, the conductor N might lead to conductor A at the point where the conductor C leads therefrom, in which case the electro-magnet D' will be in shunt around the resistance B.

Having thus fully described my invention, what I claim as new, and desire to secure by Letters Patent, is as follows:

1. In an electric meter, the combination of a translating device in the circuit of the current to be measured, said translating device varying in resistance as the current passes through it, and a current-reverser, which reverses the direction of the current through such translating device responsive to its varying resistance.

2. In an electric meter, the combination of a translating device in the circuit of the current to be measured, said translating device varying in resistance as the current passes through it, and a current-reverser, which reverses the direction of the current through such translating device responsive to its varying resistance, said current-reverser containing an electro-magnet traversed by the current to be measured.

3. In an electric meter, the combination of a translating device in the circuit of the current to be measured, said translating device varying in resistance as the current passes through it, and a current-reverser, which reverses the direction of the current through such translating device responsive to its varying resistance, said translating device consisting of a storage-battery.

4. In an electric meter, the combination of a translating device in the circuit of the current to be measured, said translating device varying in resistance as the current passes through it, and a current-reverser, which reverses the direction of the current through such translating device responsive to its varying resistance, said translating device consisting of a storage-battery and said current-reverser containing an electro-magnet traversed by the current to be measured.

5. In an electric meter, the combination of a translating device in the circuit of the current to be measured, said translating device varying in resistance as the current passes through it, and a current-reverser, which reverses the direction of the current through such translating device responsive to its varying resistance, and a registering device operated by such current-reverser.

6. An electric meter having in combination a current-reverser and a translating device, which varies in resistance as the current

passes through it, both normally at all times traversed by the current to be measured.

7. In an electric meter, the combination of a secondary battery in the circuit to be measured, the current of which alternately passes in opposite directions therethrough, means for automatically reversing such current, and a register operated by the reverse of such current.
- 10 8. In an electric meter, the combination of a register operated at each reversal of the cur-

rent to be measured with a current-reverser normally constantly traversed by the current to be measured and a varying resistance in the circuit of the current to be measured, said 15 current-reverser responsive to the variations in such resistance.

Signed this 16th day of May, 1889.
